DETACHABLE HARDWARE FOR BURIAL VAULTS

Robert N. Johnson, Bonne Terre, Mo.

Application January 8, 1954, Serial No. 402,877

16 Claims. (Cl. 27—35)

The present invention relates generally to burial vaults, and more particularly to means adapted to facilitate the handling of burial vaults, especially the dome member thereof.

More specifically, this invention pertains to detachable hardware that may be applied to a burial vault dome in order to facilitate the handling and transporting thereof, said hardware, in addition to serving as handling equipment, also serving in an ornamental capacity while in use.

The detachable hardware contemplated by the present invention has many advantages. Among them, an important advantage is that said hardware may be readily unfastened and removed from the dome after the vault has been placed on a conventional lowering device at the grave. Thus, the hardware, instead of being interred, may be employed repeatedly in serving the ends for which it is designed.

Primarily, though not exclusively, the instant equipment is designed for use in handling burial vault domes of the type disclosed in my copending application Serial No. 392,187, filed November 16, 1953, and entitled Burial Vault. As illustrated and described in my said application, the core of the vault dome member comprises a shell of steel that has been cast prior to the bonding thereto of a mastic asphalt composition covering.

This asphalt covering envelops the shell, and subsequent to the hardening thereof, a dome member is provided to the external surfaces of which molding strips and the like, also of asphalt composition, may be fused in the manner clearly set forth in the copending application aforesaid.

Heretofore, as far as I am aware, the equipment employed for handling burial vault domes of this type has been in the nature of handle and handle bar members rigid with the dome, or supported from fittings or plates permanently affixed in various manners to the sides and ends of the dome.

That is to say, conventional equipment of this nature is permanently secured to the dome member by means of bolts, screws and the like, and sometimes by means of welding. In consequence of this arrangement, the equipment can serve its purpose but once, as should be apparent. Further, because this is so, it should be manifest that the included handles and so on must of necessity be constructed inexpensively, and of comparatively inexpensive materials.

A distinct advantage provided by the present invention is that because the herein contemplated equipment may be readily unfastened and removed after serving its purposes, said equipment may be re-used time and time again. Therefore, more elaborate designs may be incorporated, and more expensive materials may be employed in its original fabrication, inasmuch as said equipment may serve to repeatedly achieve its ends, as will appear.

The primary object of the invention, therefore, is to provide decorative hardware adapted to be attached to the dome member of a burial vault assembly for handling the dome preliminary to interment thereof, and adapted to be quickly and easily removed from said dome

2

member for future re-use immediately prior to interment thereof.

In one embodiment of the invention, a pair of similar side plates, and a pair of similar end plates are provided with interengageable hinge eye segments adapted to register at the corners of the dome member for the ready insertion and removal of ornamentally headed hinge pins.

Features and advantages not specifically recited above will be apparent or pointed out in the detailed description to follow, reference being had to two sheets of drawings, wherein exemplary embodiments of my invention are clearly illustrated.

In said drawings:

Figure 1 is a side elevational view of a burial vault dome whereon one embodiment of the decorative hardware equipment of the present invention is detachably mounted;

Figure 2 is an enlarged end elevational view of the Figure 1 structure;

Figure 3 is a vertical sectional view on an increased scale, and taken on the line 3—3 of Figure 2;

Figure 4 is a horizontal sectional view taken on the line 4—4 of Figure 1, the scale of this view corresponding to that of Figure 3;

Figure 5 is a fragmentary horizontal sectional view on a further enlarged scale, particularly demonstrating the hinge interlocking arrangement obtaining at the corner portions of the dome member;

Figure 6 is an interior view drawn to the scale of Figure 5, and exhibiting a hinge element incorporated in one end of a side plate, a complementary hinge element incorporated in one end of an end plate, and a hinge pin adapted to interconnect said hinge elements;

Figure 7 is an isometric view of a hanger member;

Figure 8 is a side elevational view of a handle assembly;

Figure 9 is a side elevational view of a burial vault dome whereon another embodiment of the decorative hardware equipment of the invention is detachably mounted;

Figure 10 is an enlarged end elevational view of the Figure 9 structure;

Figure 11 is an enlarged sectional view taken along the line 11—11 of Figure 10;

Figures 12 and 13 are fragmentary sectional views on a further enlarged scale, taken respectively along the lines 12—12 and 13—13 of Figure 10;

Figure 14 is a large scale fragmentary view demonstrating a latching linkage in unlocked or open position; and

Figure 15 is a sectional view taken on line 15—15 of Figure 14.

The burial vault dome illustrated in the drawings is designated generally by the numeral 20. It comprises a preformed shell of steel 21, all surfaces of which are covered by an enveloping layer 22 of asphalt compound, in the manner clearly illustrated and described in my copending application aforesaid. Further, as also disclosed in said application, molding strips 24 are fused onto the dome member along the lower peripheral margins of the side walls 26, and the end walls 28 thereof.

In accordance with the concepts of the present invention with respect to the form thereof illustrated in Figures 1 through 8, a plurality of hanger members 30, one of which is illustrated per se in Figure 7, is permanently incorporated in the dome 20 at the time of applying the molding strips 24.

Each hanger 30 includes a flat body portion 32 that terminates at the top in a downturned hook segment 34, and at the bottom in an upturned hook segment 36.

These hangers are fashioned of inexpensive metallic material, and the exposed surfaces of them are treated so as to blend with the external finish of the dome, or with

the detachable hardware to be described. Each hanger member 30 is permanently affixed in the manner clearly illustrated in Figure 3, where it is seen that the upturned hook segment 36 engages a lower peripheral edge 38 of the dome, the flat body portion 32 lies against an external surface of the dome, and the downturned hook segment 34 extends laterally therefrom.

In affixing a molding 24, an appropriate solvent such as naphtha is first applied to one surface of the molding, whereupon the solvent treated surface is properly positioned against an exterior asphalt compound surface of the dome member 20. Thereupon, inward pressure is applied until said molding is fused onto, or merged into, the exterior dome surface aforesaid, all in accordance with the teachings of my said copending application. In consequence of the solvent treatment, the hanger surrounding region of the molding becomes sufficiently plasticized to accommodate the initial reception thereinto, and the subsequent perpendicularly disposed retention therein, of a hanger member 30.

It should thus be manifest that the present invention contemplates a dome member which is identical in all respects with that disclosed in my copending application, except that a plurality of spaced hanger members 30 is incorporated therein along the bottom peripheral margins of the side walls 26, and the end walls 28 thereof. In the exemplary dome illustrated, three spaced hangers 30 are incorporated along the bottom of each side wall 26, and two spaced hangers are incorporated along the bottom of each end wall 28.

The detachable hardware in assembly is generally designated 40, and includes: a pair of side plates 42; a pair of end plates 44; hinge connections generally designated 46 disposed at each corner of the dome; spaced integrally formed and laterally extending bosses 48 on the side plates 42; similar bosses 50 on the end plates 44; handle bars 52, welded as suggested at 54, or otherwise rigidly secured to the outer faces of the side plate bosses 48; handle bars 56, welded as suggested at 58, or otherwise rigidly secured to the outer faces of the end plate bosses 50; spaced depending loops 60 integrally formed on the side plates 42; and similar loops 6 formed on the end plates 44.

An exploded view of one of the corner connections 46 is exhibited in Figure 6. This view, with reference being had also to Figure 5, demonstrates that each extremity of the side plates 42 is interiorly recessed as at 62, whereby to receive a first hinge section 64 that is spot-welded as suggested at 66, or otherwise rigidly fastened to the side plate in such fashion that the inner faces of said hinge section and said side plate are flush. Similarly, each extremity of the end plates 44 is interiorly recessed as at 68, whereby to receive a second or companion hinge section 70 that is spot-welded as suggested at 72, or otherwise rigidly fastened to the end plate in such fashion that the inner faces of said hinge section and said end plate are flush.

The eye segments 74 of hinge section 64 project beyond the adjacent marginal edge 76 of the side plate 42 as illustrated, and in like manner, the eye segment 78 of companion hinge section 70 projects beyond the adjacent marginal edge 80 of the end plate 44. Numeral 82 designates a hinge pin, terminating at one end in an enlarged head portion 84 that facilitates manual insertion of the pin into, and extraction of the pin from, the mated hinge eye segments 74 and 78. Preferably, the head portion 84 is of a generally spherical configuration, so that, as seen to best advantage in Figure 2, an assembled hinge connection 46 presents a pleasing appearance to an observer.

Preferably also, as suggested in Figures 1 and 2, the bosses 48 and 50 are formed on the side and end plates in such fashion as to surmount the loop segments 60 and 61, respectively, thus providing a symmetrical pattern of ornamentation for the hardware.

As should be apparent from an inspection of the draw-

ings, and as will be more fully explained hereinafter, the loops 60 and 61 are formed for interengagement with the hook portions 34 of the hanger members 30. Consequently, the spacing of the hangers 30 determines the spacing of the loop segments 60 and 61, as should be understood.

An important feature of the invention, in consequence of the repetitious utilization thereof, is that the pristine fabrication of the equipment warrants a considerably greater financial outlay than is warranted in the fabrication of conventional equipment, which, after serving its purposes once, is buried in the grave.

In other words, the present invention contemplates removable decorative hardware that serves to achieve its utilitarian purposes in a highly efficient manner. Selected ornamentation such as floral wreaths, symbolic designs and so on may be engraved or embossed on the exposed surfaces of the side and end plates as suggested at 86 in Figure 2. Likewise, such embellishment may also be provided on the similar surfaces of the bosses 48 and 50 as suggested at 88 in Figures 1 and 2.

Although the manner in which the thus far described form of the invention may be repeatedly utilized is deemed to be apparent, a brief explanation will now be given.

It will be assumed in the interest of brevity that ordinarily all burial vault domes of the type under consideration are similarly dimensioned with respect to their external rectangular peripheries, irrespective of the size of the therein to be enclosed casket. Based on such premise, the detachable organization of side and end plates is so dimensioned interiorly that a clamping action between the outer side and end wall surfaces of the dome 20, and the inner surfaces of the side and end plates will be produced, in consequence of the insertion of a hinge pin 82 into the registering eye segments 74 and 78 of the fourth or final hinge connection 46.

Stated otherwise, when the fourth or final hinge connection 46 is sequentially effected by the insertion of the fourth or final hinge pin 82, the side plates 42 and the end plates 44 are caused to engage against the contiguous side and end walls of the dome 20 with sufficient pressure to maintain said plates in the disposition thereof particularly exhibited in Figures 1 through 3. In such disposition of the side and end plates 42 and 44, respectively, the downturned upper hook segments 34 of the hangers 30 are interlocked with the depending loop formations 60 and 61 of said plates, as clearly demonstrated in Figure 3.

From the foregoing description and explanation augmented by an inspection of Figures 1 through 8 of the drawings, it is believed that a comprehensive understanding of the first embodiment of my invention may be had. After the detachable decorative hardware assembly 40 has served to achieve its intended functions, the hinge pins 82 may be extracted manually, followed by disengagement of the loop segments 60 and 61, whereupon the equipment may be reutilized on another burial vault dome member, as should now be clear.

Assuming now that in consequence of the expense involved, a situation were to arise wherein the cost of the detachable hardware assembly 40 would be prohibitive, the present invention contemplates comparatively inexpensive means for handling the dome 20, in the form of handle assemblies such as that portrayed in Figure 8 and designated in its entirety by the numeral 92. The exemplarily illustrated handle assembly 92 includes a handle proper 93, and a dependently supported loop member 94 adapted for interengagement with one of the downturned hook extremities 34 of the permanently incorporated hangers 30. The utility of a plurality of handle assemblies 92 in lieu of the handle bar arrangement is deemed obvious.

Another form of my invention is illustrated in Figures 9 through 15, wherein the dome member and its con-

stituent parts are identified by the same reference numerals employed for that purpose hereinbefore.

In this form of the invention, the hanger members 30 are dispensed with, the detachable hardware assembly 100 being securely clamped to the dome side and end walls in such fashion that when a lifting action is applied to the included handle bars 102, the hardware will exert additional pressure against the outer surfaces of the dome, as will appear.

The assembly 100 includes in addition to said handle bars: a pair of side plates generally designated 104; a pair of end plates generally designated 106; hinge connections generally designated 108 disposed at each corner of the dome; and spaced integrally formed laterally extending bosses 110 on the side plates 104, the aforesaid handle bars 102 being welded, as suggested at 112, or otherwise rigidly secured to the outer faces of said bosses.

Preferably, as Figure 9 demonstrates, each side plate 104 includes spaced upper and lower rails 114 and 116 respectively, that are integrally cast with the bosses 110. Each of the side plate rails 114 and 116 has its extremities interiorly recessed as at 118, whereby to receive a hinge section 120 that is spot-welded, or otherwise rigidly fastened to the rail in such fashion that the inner faces of the hinge section and said rail are flush, and the eye segments 122 of said hinge section project beyond the adjacent marginal edge 124 of the rail.

As particularly demonstrated in Figures 10, 11 and 13, each end plate 106 includes: two angularly disposed and over-lapping links 125 and 126; four hinge sections 128, 130, 132 and 134; a pivotal connection 136 between one end of the link 125 and the offset extremity 138 of the hinge section 134; a pivotal connection 140 between one end of the link 126 and the flat extremity 142 of the hinge section 132; two similar lock or latch bars 144 and 146; a first pivotal connection 148 between one end portion of the latch bar 144 and the free extremity of the link 125; a second pivotal connection 150 between the opposite end portion of latch bar 144 and the offset extremity 152 of hinge section 128; a first pivotal connection 154 between one end portion of the latch bar 146 and the free extremity of the link 126; and a second pivotal connection 156 between the opposite end portion of latch bar 146 and the offset extremity 158 of hinge section 130.

That end of latch bar 144 having the pivotal connection 148 aforesaid has an integral extension thereon in the form of a hook 160, and that end of latch bar 146 having the said pivotal connection 154 has an integral extension thereon in the form of a similar hook 162. Each of the four hinge sections 128, 130, 132 and 134 has integrally formed thereon a projecting eye segment 164 adapted to register with the similar segments 122 of the side plates, and to receive hinge pins 166.

Preferably, in this form of the invention, the hinge pins 166 are not removable, the detaching operation being accomplished by swinging the latch bars 144 and 146 from the locked positions thereof exhibited in Figure 10, to the released or unlocked position thereof demonstrated in Figures 14 and 15 with respect to latch bar 146.

It is to be noted that the interior periphery of the assembly 100 is accurately dimensioned for vault domes of a certain size, so that when said assembly is properly attached, the side plates 104 and the hinge sections of the end plates 106 frictionally engage the side and end walls 26 and 28, respectively, of the dome member 20. Manifestly, assuming that said dome member were elevated by means of the handle bars 102, the degree of frictional engagement would be increased in consequence of the illustrated criss-cross arrangement of the components comprising the end plates 106.

Reverting to the frictional engagement obtaining between the dome member and the assembly 100, it should be remembered that the links 125 and 126 are each pivotally mounted at one end, so that the said frictional engagement is effected when the latch bars 144 and 146

are swung counterclockwise and clockwise, respectively, into the locked positions thereof exhibited in Figure 10. In order to detach the assembly 100 for future reuse, the latch bars are swung counterclockwise, thereby automatically expanding said assembly sufficiently for its ready removal from the dome.

In the fabrication of this form of the invention, a considerably greater financial outlay is also warranted, inasmuch as the hardware may be used time and again. Embossings and engravings as suggested at 168 in Figure 1 are provided on the exterior faces of the bosses 110 for decorative purposes. The rails 114 and 116 may also be embellished with wreaths, symbolic designs, and so on. If desired, a suitable ornamental cover plate may be applied to the end walls 28 of the dome, in order to shield the end plates 106 from view at such times when the dome is on display.

It is believed that the foregoing description, augmented by an inspection of the drawings, provides a comprehensive disclosure of the invention. The structural elements illustrated and described obviously may be modified in some respects without departing from the fundamental concepts of the invention. Wherefore, it is to be understood that the invention contemplates any and all modified or equivalent structure that may fall within the scope of the claims hereunto appended.

What is claimed is:

1. Decorative hardware mounted on the dome of a burial vault assembly, including in combination: a hinged-ly connected organization of side and end plates extending substantially completely transversely of and clampingly engaging, respectively, the side and end walls of the dome; and manually engageable means horizontally spaced from and rigid with the side plates for handling and transporting said dome; said hingedly connected organization of side and end plates including manually removable means for disconnecting said plates to detach said hardware.

2. Decorative hardware mounted on the dome of a burial vault assembly, including in combination: a hinged-ly connected organization of side and end plates extending substantially completely transversely of and clampingly engaging, respectively, the side and end walls of the dome; and manually engageable means horizontally spaced from and rigid with the side and with the end plates for handling and transporting said dome; said hingedly connected organization of side and end plates including manually removable means for disconnecting said plates to detach said hardware.

3. Detachable hardware for handling and transporting a burial vault dome member of the type described, said hardware including in assembly: pairs of horizontally spaced side and end plates engaging the side and end walls respectively of the dome member, each of said side plates being secured to a handle horizontally spaced therefrom; a hinge connection joining the extremities of adjacent side and end plates at each corner of the dome member; and means maintaining the assembled hardware releasably in position on the dome member.

4. Detachable hardware for handling and transporting a burial vault dome member of the type described, said hardware including in assembly: pairs of horizontally spaced side and end plates engaging the side and end walls respectively of the dome member; a plurality of longitudinally spaced laterally extending bosses integrally formed on the side plates; a hinge connection joining the extremities of adjacent side and end plates at each corner of the dome member; a handle bar spaced from each side plate and rigidly secured to the bosses of each side plate; and means maintaining the assembled hardware releasably in position on the dome member.

5. Removable equipment for handling and transporting a burial vault dome of the type described, said equipment including: pairs of horizontally spaced side and end plates adapted to engage the side and end walls respec-

tively of the dome; a plurality of longitudinally spaced laterally extending bosses formed integrally with each side plate, the surface of said bosses and side plates that will be exposed when the equipment is in use being embellished with ornamentation; hinge connections joining the extremities of adjacent side and end plates at the corners of the dome; a handle bar spaced from each side plate and rigid with the bosses of each side plate; and means to retain the equipment detachably in position on the dome.

6. Removable equipment for handling and transporting a burial vault dome of the type described, said equipment including: pairs of horizontally spaced metallic side and end plates adapted to engage the side and end walls respectively of the dome; a plurality of longitudinally spaced laterally extending bosses formed integrally with each side and end plate, the surfaces of said bosses and side plates that will be exposed when the equipment is in use being embellished with ornamentation; separable hinge connections joining the extremities of adjacent side and end plates at the corners of the dome; a handle bar rigid with the bosses of each side and end plate; and depending loop segments formed integrally with the side and end plates beneath each of the bosses aforesaid, each loop segment being adapted to engage the upper end hook portion of a hanger member permanently attached to the dome.

7. In combination with a burial vault dome of the type described, said dome having molding strips fused onto the lower peripheral margins of the side and end walls thereof: a plurality of spaced hanger members each permanently incorporated in the dome at the time of applying said molding strips, and a decorative hardware assembly adapted to be removably mounted on the dome in cooperative disposition relatively to said hanger members for handling and transporting said dome, the hardware assembly including: hinged connected side and end plates to clampingly engage the side and end walls of the dome; spaced depending loop segments integrally formed on said plates each engaging the upper end portion of one of said hanger members; and a handle bar rigidly secured to each of said side and end plates.

8. The structure set forth in claim 7, wherein each of the recited hanger members includes a flat body portion terminating at the top in a downturned hook segment, and at the bottom in an upturned hook segment, said hook segments extending laterally from the flat body portion in opposite directions relatively to each other.

9. In combination with a burial vault dome of the type described, said dome having molding strips fused onto the lower peripheral margins of the side and end walls thereof: a plurality of spaced hanger members each permanently incorporated in the dome at the time of applying said molding strips, each hanger member including a flat body portion terminating at the top in a laterally extending downturned hook segment; and a plurality of handle assemblies for transporting said dome, each assembly including a handle member, and a loop member dependently supported therefrom for interengagement with the downturned hook segment of one of said hanger members.

10. Detachable hardware for a burial vault dome in combination with a plurality of spaced hanger members of the character described that are permanently incorporated in said dome, said hardware comprising: a pair of side plates; a pair of end plates; hinge assemblies at each corner of the dome connecting the adjacent ends of one side and one end plate; a plurality of spaced laterally extending bosses formed integrally with each side plate; a plurality of similar bosses formed integrally with each end plate; a handle bar rigidly affixed to the outer faces of the bosses on each side plate; a handle bar rigidly affixed to the outer faces of the bosses on each end plate; and a plurality of spaced depending loop segments in-

tegrally formed on the side and end plates, each loop segment interengaging a hook portion of one of the hanger members.

11. The detachable hardware for a burial vault dome set forth in claim 10, wherein each of the recited hinge assemblies comprises: a first hinge section disposed in an interiorly recessed extremity of a side plate and rigidly secured thereto; a second or companion hinge section disposed in an interiorly recessed extremity of an end plate and rigidly secured thereto, the eye segments of said hinge sections projecting beyond the adjacent marginal edges of said plates in registering disposition; and a hinge pin extending through said registering eye segments, said hinge pin being surmounted by an enlarged head portion facilitating the manual insertion of the pin into, and extraction of the pin from, said eye segments.

12. In a detachable organization of side and end plates for engaging against the side and end walls respectively of a burial vault assembly dome member of the character described: a hinge section rigidly mounted at each extremity of the side plates; a companion hinge section rigidly mounted at each extremity of the end plates, each hinge section including at least one integral eye segment projecting beyond the adjacent marginal edge of the plate whereon it is mounted; a hinge pin for connecting the eye segments of contiguous hinge sections; and a handle bar rigidly secured in horizontally spaced relation to each side and end plate.

13. Detachable hardware for the dome of a burial vault assembly, including in combination: side and end plates for engaging the side and end walls respectively of the dome, each of said side plates comprising spaced upper and lower rails rigid with a plurality of longitudinally spaced bosses extending laterally therefrom; hinge connections joining the extremities of adjacent side and end plates at the corners of the dome; manually operable latching means incorporated in the end plates for releasably clamping said hinge-connected plates in position on the dome; and manually engageable means rigidly secured to the bosses of each side plate for handling and transporting the dome.

14. Detachable equipment for handling and transporting a burial vault dome of the character described, said equipment including in combination: pairs of horizontally spaced metallic side and end plates in frictional engagement with the side and end walls respectively of the dome; a plurality of longitudinally spaced laterally extending bosses formed integrally with each side plate, the surfaces of said bosses that will be exposed when the equipment is in use being embellished with ornamentation; permanent hinge connections joining the extremities of adjacent side and end plates at the corners of the dome; a handle bar rigid with the bosses of each side plate; and manually operable latching means on the end plates to releasably maintain said pairs of side and end plates in the aforesaid frictional engagement with the side and end walls of the dome.

15. The structure set forth in claim 14, wherein each of the recited end plates includes: an inner angularly disposed link; a flat lower hinge section; a pivotal connection between one end of said link and the lower hinge section; a first latch bar; a pivotal connection between the other end of said link and one end of said latch bar; a first offset upper hinge section; a pivotal connection between the other end of said latch bar and the offset portion of said upper hinge section; an outer angularly disposed link overlapping said inner link; an offset lower hinge section; a pivotal connection between one end of the outer link and the offset portion of said lower hinge section; a second latch bar; a pivotal connection between the other end of the outer link and one end of the second latch bar; a second offset upper hinge section; and a pivotal connection between the other end of said second

latch bar and the offset portion of said second upper hinge section.

16. In a hingedly connected rectangular assembly of spaced side and end plates adapted to encompass the side and end walls of a burial vault dome, manually operable latch means on said end plates for first contracting said assembly into frictional engagement with said walls, and for subsequently expanding said assembly to facilitate the removal thereof from said dome.
